UNITED STATES PATENT OFFICE.

ALLEN W. PHILLIPS, OF PROVIDENCE, RHODE ISLAND.

DESK-BOX.

SPECIFICATION forming part of Letters Patent No. 401,757, dated April 23, 1889.

Application filed November 19, 1888. Serial No. 291,276. (No model.)

To all whom it may concern:

Be it known that I, ALLEN W. PHILLIPS, a citizen of the United States, residing at Providence, in the county of Providence and State 5 of Rhode Island, have invented a new and Improved Desk-Box, of which the following is a specification.

My invention consists of a box adapted to contain stationery materials conveniently arranged, the lid whereof affords an inclined surface on which to rest the paper in writing, the rear portion beyond the lid being flat. Said box is provided with an inkstand permanently attached thereto and extending 15 through the top of the box. The interior is provided with a false bottom.

In the accompanying drawings, illustrating my invention, Figure 1 is a top view of the same. Fig. 2 is a sectional elevation on line 20 *xx* of Fig. 1.

B is the box; L, the lid inclined, as shown; and T, the flat top portion.

F is the false bottom, having about the same inclination as the lid. Upon this are placed 25 the sheets of letter-paper and envelopes, as

shown. The front edge of the false bottom rests on the bottom of the box proper, so as to make the space available for stationery about equal in depth to the front or shallow-est part of the box. The ink-bottle E occu- 30 pies the deepest part of the box, as shown, and extends through the flat top. The cap *c* of the bottle is removable from the outside. This arrangement comprises a most conven- 35 ient and serviceable article, affording a use- ful receptacle for stationery materials, and at the same time furnishing a convenient desk-surface for writing, with the ink permanently at hand.

What I claim, and desire to secure by Let- 40 ters Patent, is—

A box for stationery purposes, consisting of the inclined lid L, the flat portion T, and the inclined false bottom F, combined with the ink-receptacle E, substantially as described, 45 for the purpose specified.

ALLEN W. PHILLIPS.
